UNITED STATES PATENT OFFICE.

WILLIAM A. LUDEKE, OF ROCHESTER, NEW YORK.

CHILD'S COIN BANK OR SAFE.

No. 910,699.

Specification of Letters Patent.

Patented Jan. 26, 1909.

Application filed May 16, 1908. Serial No. 433,747.

To all whom it may concern:

Be it known that I, WILLIAM A. LUDEKE, a citizen of the United States, residing at Rochester, in the county of Monroe and State of New York, have invented new and useful 5 Improvements in Children's Coin Banks or Safes, of which the following is a specification.

This invention relates to a toy bank or safe and relates more particularly to a coin 10 chute provided with means for preventing the coins from being extracted from the safe through the chute.

The invention has for one of its objects to provide a device of this character which is of 15 extremely simple and inexpensive construction, thoroughly reliable and effective in use and composed of comparatively few parts so designed as to prevent tampering with the bank.

20 Another object of the invention is the provision of a coin chute having pivoted guards so disposed that when the bank is inverted or held in position for attempting to remove the coins, the said guards will gravitate to a position for preventing the coins from dropping 25 out of the chute.

With these objects in view and others as 30 will appear as the description proceeds, the invention comprises the various novel features of construction and arrangement of parts which will be more fully described hereinafter and set forth with particularity in the claim appended hereto.

In the accompanying drawings which 35 illustrate one of the embodiments of the invention:—Figure 1 is a vertical section of a child's bank equipped with the improved chute. Fig. 2 is a section on line 2—2 of Fig. 1. Fig. 3 is a view similar to Fig. 2 40 showing the bank inverted. Fig. 4 is a detail view of one of the guard members.

Similar reference characters are employed to 45 designate corresponding parts throughout the views.

Referring to the drawing, A designates a bank or safe of any approved construction which has in its top a mouth 1 through which the coins are introduced and under the mouth is a chute 2 of rectangular horizontal 50 cross section formed with flanges 3 at its top for receiving rivets or other fastenings 4 whereby the chute is secured in position. This chute is provided with vertical slots 5 in its opposite walls for receiving the guard 55 members B. In the present instance the chute is equipped with two sets of guard

members so arranged to prevent smaller coins from being extracted through the chute. The corresponding members B of both sets are mounted to swing on a rod 6 60 suitably secured to the chute and extending across the slots 5. The lower part 7 of each member B is enlarged and the apertured lug 8 through which the rod 6 passes is so arranged that the said member will hang in 65 the position shown in Fig. 2. The opposed faces 9 of opposite members B are inclined to each other so as to permit a coin dropped through the chute to spread the members apart for enabling the coin to drop into the 70 bank. The upper extremities 10 project above the lugs 8 and are adapted to enter the slots 5 and extend across the chute when the bank is tilted in one direction or the other and inverted to thus constitute keepers 75 for preventing coins from being extracted. When the bank is inverted the members B will assume the position shown in Fig. 3, the members being so weighted as to readily swing back and forth as the bank is tilted or 80 inverted and are adapted at all times to prevent coins from being removed through the chute. When one member B tilts its short arm will engage the short arm of the other companion member and cause the latter to 85 tilt in the same direction so that both members of each set will extend across the chute and the weighted ends lie on the same side of the latter.

From the foregoing description taken in 90 connection with the accompanying drawing, the advantages of the construction and method of operation will be readily apparent to those skilled in the art to which the invention appertains and while I have described the principles of operation of the invention together with the device which I now consider to be the best embodiment thereof, I desire to have it understood that the device shown is merely illustrative and 95 that such changes may be made when desired as are within the scope of the claim.

Having thus described the invention, what I claim as new and desire to secure by Letters Patent is:—

A coin bank comprising a casing having a coin opening in its top, a rectangular chute consisting of a tubular structure having oppositely-disposed flanges at its upper end, said flanges being disposed against the inner 110 surface of the casing top at opposite sides of the coin opening, fastenings for securing the

flanges to the said casing, the opposite walls of the chutes having slots extending upwardly from the lower end of the chute, bearings arranged on the opposite sides of the chute, horizontal rods at opposite sides of the chute and disposed in the bearings and extending across the said slots, and guard members pivotally mounted on the rods to swing thereon into and out of the slots of the chute to prevent coins from being re-

moved when the bank is inverted, said guards having weighted arms normally disposed below the chute and between which the coins drop into the bank.

In testimony whereof I affix my signature ¹⁵ in presence of two witnesses.

WILLIAM A. LUDEKE.
